UNITED STATES PATENT OFFICE.

EDWARD VOLCANSEK, OF CLEVELAND, OHIO.

DESIGN FOR A COMBINED PISTOL AND SWORD HILT.

50,979.

Specification for Design.

Patented June 26, 1917.

Application filed January 24, 1917. Serial No. 144,308. Term of patent 7 years.

To all whom it may concern:

Be it known that I, EDWARD VOLCANSEK, a subject of the Emperor of Austria, residing at Cleveland, in the county of Cuyahoga and State of Ohio, have invented a new, original, and ornamental Design for a Combined Pistol and Sword Hilt, of which the following is a specification, reference being had to the accompanying drawing, forming a part thereof.

The figure is a view in side elevation of

my design for combined pistol and sword hilt, a portion of the sword blade being shown by dotted lines.

I claim:—

The ornamental design for a combined pistol and sword hilt, as shown.

EDWARD VOLCANSEK.
